Radio Corporation of America, a corporation
of Delaware

Application March 29, 1929, Serial No. 350,884,
Renewed January 24, 1933

20 Claims. (Cl. 250—33)

This invention relates to antennas, and more particularly to directional antennas for use with energy of very short wave length.

In my copending application Serial Number 231,804, filed November 8, 1927, which has issued as U. S. Patent No. 1,821,402, granted September 1, 1931, I have disclosed a directional antenna comprising a pair of relatively closely spaced feeder members extending in the direction of desired communication, with a plurality of antenna conductors extending transversely and externally of the feeder members, and loosely coupled thereto through relatively high impedances. The primary object of my present invention is to improve the directional properties of such an antenna. To this end I now have devised an antenna which, like that already referred to, includes a pair of relatively closely spaced feeder members extending in the direction of desired communication, and a plurality of antennas coupled thereto, but in accordance with the present invention, each of these antennas comprises a pair of conductors which diverge in the direction of desired communication.

Such a pair of diverging conductors constitutes an antenna, which is itself somewhat directive in the direction of divergence of the conductors, the operation being in this respect considerably superior to that of a simple doublet. In consequence, the directional property of the complete antenna system is also increased, being approximately equal to the product of the directivity of the system when nondirectional antennas are used, and the directivity of the individual antennas comprising the system.

In order that the antennas may all aid one another they should operate at a phase displacement equal to the phase displacement of the signalling wave in space over a distance equal to the distance between the points of coupling of the antennas to the feeder members. Furthermore, energy should be transferred along the diverging conductors at such a velocity that the equivalent velocity in the direction of communication, that is, the cosine component, is equal to the velocity of the signalling wave in space. If the angle of divergence of the conductors is very small then the cosine is nearly unity, and it may be assumed that the usual velocity along the conductors will be sufficiently great. However, if the angle of divergence is very great, the velocity along the conductors must be considerably increased, and to provide for the necessary increase in velocity I insert series condensers in the antenna conductors.

Assuming that the antennas are made to operate at the proper phase difference, and that the proper velocity is obtained along the antenna conductors, it is still necessary that the energy be made to flow along the feeder members at or near the velocity of the wave in space. The velocity which normally would exist on a pair of feeder members is satisfactory, assuming no loading, but upon loading the feeder members with the antennas, this velocity is apt to be greatly reduced. To avoid this effect I couple the antennas to the feeder members through high impedances which make the coupling sufficiently loose so that the velocity of energy transfer on the feeder members is not materially reduced.

In order to make the antenna unidirectional it is desirable to prevent reflection of energy on either the antenna conductors or the feeder members. In the case of a receiving antenna, energy approaching from the rear, if reflected, acts like energy approaching from the front of the antenna. In order to prevent the possibility of reflection I employ surge impedances at the remote end of the feeder members, and preferably also at the open ends of the diverging antenna conductors.

My invention is further described in the following specification, which is accompanied by a drawing in which Figure 1 indicates one form of my invention; Figure 2 is a modification in which the antenna conductors have a large angle of divergence; while Figure 3 is a vector diagram explanatory of Figure 2.

Referring to Figure 1 it will be seen that the antenna includes a pair of relatively closely spaced feeder members 2, which extend in the direction of desired communication, and which at the near end are connected to a receiver 4 through a transmission line 6, and at the far end are closed by a surge impedance 8. To the feeder members at spaced intervals are coupled antennas, each comprising a pair of conductors 10 and 12 diverging in the direction of desired communication. The remote ends of these conductors are preferably also closed with surge impedances, here numbered 14. The latter surge impedances are especially desirable if only a few antennas are used, but are practically dispensable if a large number of antennas are used.

The antennas are coupled to the feeder members through impedances of high magnitude, taking the form, in the specific case here illustrated, of small coupling condensers 16. The object of these impedances is to couple the antennas to the feeder members loosely, for in such

case I have found that the loading of the antennas on the feeder members does not very greatly reduce the velocity of energy transfer along the feeder members, so that the phase displacement between the energies on the antennas, which is equal to the phase displacement of the wave travelling in space, is kept equal to that of the energy travelling on the feeder members.

Figure 2 is quite similar to Figure 1, except that in this case the antenna conductors diverge very much more abruptly. In order to speed up the velocity of energy flow along the antenna conductors they are arranged with series condensers 20. The object of these condensers may better be explained by reference to Figure 3, in which it will be seen that if the dimension AC is to equal the velocity of the wave in space, the velocity AB, along the antenna conductors, must be made greater in proportion to the secant of the angle of divergence of the antenna conductors, for the space wave, moving parallel to the feeder members, cuts the antenna conductors at a more rapid rate owing to the slope of the antenna conductors. The insertion of series condensers serves to increase the velocity of flow of the energies along the conductors, and so to retain the desired initial phase displacement until these energies reach the feeder members.

Surge impedances may be used at the open ends of the antenna conductors, as at 14, but with the close spacing indicated in Figure 2, they are not essential.

The plane of polarization of this antenna corresponds to the plane of the antenna.

When the antenna is used for transmission considerable loss may take place in the surge impedances 8 and 14, and these should preferably be eliminated, reflection being prevented by proper attenuation of the transmission energy along the antennas and feeder members.

I claim:

1. The combination with a single receiver of a directional antenna system including a pair of relatively closely spaced feeder members connected to said receiver extending in the direction of desired communication, and a plurality of antennas simultaneously coupled thereto, each of said antennas comprising a pair of conductors which diverge in the direction of desired communication.

2. A directional antenna system including a pair of relatively closely spaced feeder members extending in the direction of desired communication, a plurality of antennas loosely coupled thereto at spaced intervals through impedances of relatively high magnitude, each of said antennas comprising a pair of conductors which diverge in the direction of desired communication.

3. A directional antenna system including a pair of feeder members extending in the direction of desired communication, and a plurality of antennas coupled to the feeder members at spaced intervals, each of the said antennas comprising a pair of conductors which diverge in the direction of desired communication, and which are arranged to operate at a phase difference equivalent to their spacing along the feeder members.

4. A directional antenna including a pair of feeder members extending in the direction of desired communication, and a plurality of antennas coupled thereto at spaced intervals, each of said antennas comprising a pair of conductors which diverge in the direction of desired communication.

munication, said conductors being provided with series condensers whereby the antennas may be made to operate at phase differences equivalent to their spacing along the feeder members.

5. A directional receiving antenna including a pair of relatively closely spaced feeder members extending in the direction of desired reception, a plurality of collecting antennas loosely coupled to the feeder members at spaced intervals through relatively high impedances, each of said antennas comprising a pair of pick-up wires diverging in the direction of the desired transmitting station, in order to increase the directivity of the antenna system.

6. A directional receiving antenna including a pair of relatively closely spaced feeder members extending in the direction of desired reception, a surge impedance connected at the remote ends of the feeder members, a plurality of collecting antennas loosely coupled to the feeder members at spaced intervals through relatively high impedances, each of said antennas comprising a pair of pick-up wires diverging in the direction of the desired transmitting station, in order to increase the directivity of the antenna system.

7. A directional receiving antenna including a pair of relatively closely spaced feeder members extending in the direction of desired reception, a plurality of collecting antennas loosely coupled to the feeder members at spaced intervals through relatively high impedances, each of said antennas comprising a pair of pick-up wires diverging in the direction of the desired transmitting station, and surge impedances connected at the remote ends of the feeder members and the antennas, in order to prevent back end pick-up.

8. In an extensive antenna system for directional communication, a plurality of spaced feeder members extending in the direction of desired communication, a plurality of auxiliary members connected to each of said spaced feeder members and diverging in the direction of desired communication, and means in each of said auxiliary members for insuring that the energy flowing therein is in phase with the energy in the feeder members.

9. In an extensive directional antenna system, a plurality of linear members extending in the direction of desired communication and connected at the far end through an impedance, a plurality of auxiliary members spaced in pairs along said linear members and coupled thereto, said auxiliary members diverging in the direction of communication, and means in each of said auxiliary members for determining the electrical length thereof such that each member has a phase difference bearing a definite relation to its physical spacing along said linear members.

10. In a directional antenna system a pair of spaced feeders extending in the direction of desired communication, a plurality of pairs of auxiliary members coupled to said feeder members and spaced therealong, each of said auxiliary members being inclined towards the desired direction of communication, an impedance connecting the terminal of each auxiliary member to ground, and series capacities in each of said auxiliary members.

11. In a directional antenna system, a pair of spaced feeders extending in the direction of desired communication, a plurality of pairs of auxiliary members coupled to said feeder members and arranged at an angle with the desired direction of communication, those terminals of said

- auxilliary members which are not coupled to said feeders being effectively coupled together by a resistance connection. 17. In a directional antenna system, high frequency apparatus, a two wire transmission line connected to said high frequency apparatus, a pair of antenna elements diverging in the desired direction of communication and coupled to said transmission line, lumped reactances serially connected in each of said elements, and a surge impedance connected across that end of said transmission line which is located away from said high frequency apparatus. 80
12. In a directional antenna system, a pair of spaced feeders extending in the direction of desired communication, a plurality of pairs of auxilliary members coupled to said feeder members and arranged at an angle with the desired direction of communication, those terminals of 10 said auxilliary members which are not coupled to said feeders being effectively coupled together by a resistance connection, and series reactances in each of said auxilliary members. 85
13. In a directional antenna system, high frequency apparatus, a pair of spaced feeder members connected to said high frequency apparatus and extending in the direction of desired communication, a plurality of pairs of auxiliary members coupled to said feeder members and arranged at an angle with the desired direction of communication, series reactances in each of said auxiliary members, and a surge impedance across that end of said feeder members located away from said high frequency apparatus. 90
14. A directional antenna system comprising a two wire transmission line, a pair of linear antenna elements diverging in the desired direction of communication, the more closely spaced ends of said diverging elements being coupled to said transmission line, and a circuit including a resistance effectively coupling together the ends of said linear elements which are spaced farther apart. 95
15. A directional antenna system comprising a two wire transmission line, a pair of antenna elements diverging in the desired direction of communication, the more closely spaced ends of said diverging elements being coupled to said transmission line, a circuit including a resistance effectively coupling together the ends of said antenna elements which are spaced farther apart, and series reactances in each of said antenna elements. 100
16. In a directional antenna system, high frequency apparatus, a two wire transmission line connected to said high frequency apparatus, a pair of linear antenna elements diverging in the desired direction of communication, the more closely spaced ends of said diverging elements being coupled to said transmission line, and an impedance connected across that end of said transmission line which is located away from said high frequency apparatus. 105
17. In a directional antenna system, high frequency apparatus, a two wire transmission line connected to said high frequency apparatus, a pair of linear antenna elements diverging in the desired direction of communication, the more closely spaced ends of said diverging elements being coupled to said transmission line, a circuit including a resistance effectively connecting together the ends of said linear elements which are spaced farther apart, and a surge impedance connected across that end of said two wire transmission line which is located away from said high frequency apparatus. 110
18. In a directional antenna system, high frequency apparatus, a two wire transmission line connected to said high frequency apparatus, a pair of linear antenna elements diverging in the desired direction of communication, the more closely spaced ends of said diverging elements being coupled to said transmission line, a circuit including a resistance effectively connecting together the ends of said linear elements which are spaced farther apart, and a surge impedance connected across that end of said two wire transmission line which is located away from said high frequency apparatus. 115
19. In a directional antenna system, high frequency apparatus, and a two wire transmission line connected to said high frequency apparatus, a pair of antenna elements diverging in the desired direction of communication, the more closely spaced ends of said diverging elements being coupled to said transmission line, lumped reactances serially connected in each of said elements, a circuit including a resistance effectively connecting together the ends of said linear elements which are spaced farther apart, and a surge impedance connected across that end of said two wire transmission line which is located away from said high frequency apparatus. 120
20. In a directional antenna system, high frequency apparatus and a two wire transmission line connected to said high frequency apparatus and extending in the direction of desired communication, a pair of linear antenna elements coupled to said two wire line and arranged at an angle with the desired direction of communication, the more closely spaced ends of said antenna elements being coupled to said transmission line, and a surge impedance coupling together the ends of the wires of said transmission line furthest away from said high frequency apparatus. 125
